UNITED STATES PATENT OFFICE.

ERVIN E. SPLETTER, OF MONTEVIDEO, MINNESOTA.

OIL BURNER.

Application filed February 23, 1926. Serial No. 89,841.

This invention relates to devices or apparatus for burning hydrocarbons, commonly known as oil burners.

It is the main object of the invention to provide an extremely simple but highly efficient oil burner provided with means for thoroughly vaporizing fuel to insure a steady, even flow of generated vapor through the burner. It is a well known fact that unless the liquid fuel is exposed in the vaporizing coil to a practically constant heat, affecting all parts of said coil evenly, the vapor will be delivered in puffs, causing the flame in the combustion chamber to increase or diminish at regular intervals and often resulting in the burner being extinguished with the attendant likelihood of a bad explosion.

A further object of the invention is to provide such a device having its vaporizing coil connected at its lower end to the source of fuel supply and its upper end with the burner disposed therebelow, the conduit of said burner being disposed in close relation to the side of said coil and in position to be strongly heated through practically its entire height.

It is a more specific object of the invention to provide an oil burner having a casing disposed above the burner proper in vertical alignment therewith and having a vaporizing coil encircling said casing in close relation thereto, the lower convolution of said coil being connected to the fuel supply and the upper convolution of said coil being connected to a vertical conduit extending downwardly between the inner side of the coil and said casing, whereby the hottest portion of the coil will be of course the top portion directly communicating with the burner and whereby the conduit connecting the burner with said top portion will be subjected to intense heat from the combustion chamber.

These and other objects of the invention will be apparent from the following description made in connection with the accompanying drawings, wherein like characters refer to similar parts throughout the several views, and in which

Fig. 1 is a side elevation of the preferred form of the invention connected to a source of fuel supply,

Fig. 2 is a plan view of the same, and

Fig. 3 is a plan view showing a modified form of burner wherein the conduit con-

necting the vaporizing coil with the burner proper is disposed on the outer side of the coil in close relation thereto.

In the drawings a liquid fuel reservoir is indicated by the numeral 4, having its lower end connected with a vertical delivery conduit 5.

In the preferred form of the invention a substantially cylindrical burner 6 is provided adapted to rest on a supporting surface having in its top face a plurality of spaced jet outlets 6^a. The sides and bottom of burner 6 are preferably covered with a layer of asbestos or other insulation 7. Above burner 6 with its axis substantially coincident with the axis of said burner a perforated cylindrical casing 8 is disposed, supported in spaced relation to the top of the burner 6 by means of a plurality of circumferentially arranged angle straps 9.

A vaporizing coil 10 is preferably formed from tubing of elliptical cross section whereby a slightly greater amount of surface will be exposed to the heat at the sides of casing 8. The lowermost convolution of coil 10 is connected by a substantially horizontal conduit 11 to fuel delivery conduit 5. A valve 12, preferably of the needle type, is interposed in conduit 11 controlling the flow of fuel to coil 10. The top convolution of coil 10 is connected by a preferably straight vertical conduit 13 with one side of the burner 6. It will be noticed that in the preferred form of the invention each convolution of coil 10 is provided with a relatively small outwardly projecting bulge 10^a, the bulges on the several convolutions being vertically aligned and affording space to accommodate vertical conduit 13. The delivery conduit from the vaporizing coil is thus held in very close relation to the side of casing 8, which forms the combustion chamber whereby intense heat may be applied to said conduit throughout practically its entire length. The chamber within burner 6 is preferably filled with loosely packed asbestos α , or other noninflammable material and the conduit 13 as well as the upper convolution of the coil 10 may also be filled with such material if desired.

The employment of this material in the conduit 13 and burner chamber has been found to materially assist in insuring an even flow of vapor through the jet orifices 6^a.

The form of the invention illustrated in Fig. 3 is identical with the preferred form

with the exception that the vaporizing coil indicated by the numeral 15 is made up of a plurality of spiral convolutions without the bulges 10^a and that the conduit 16 connecting the upper end of the vaporizing coil with the burner is disposed on the outer side of the vaporizing coil in close relation thereto. Conduit 16 of course will not receive as great an amount of heat as the conduit 18 10 in the preferred form but the close relation of this conduit to the hot coil results in an even delivery of vapor to the burner proper. The lower portion of conduit 16 may be insulated if desired to increase efficiency of 15 the device.

In operation the fuel will be fed to the lower end of the coil 10, the flow controlled by valve 12. After the vapor has been generated the combustion will take place in the 20 combustion chamber within casing 8, oxygen being applied through the bottom of the casing and the plurality of perforations in the walls of said casing.

The vaporizing coil will be intensely and 25 evenly heated, since its axis is coincident with the axis of burner 6 and casing 8. The top of coil 10 will of course be the hottest part of the coil, since the heat will rise. I introduce my fuel, therefore, at the bottom 30 of the coil and deliver the vapor from the top of the coil to the side of burner 6. The conduit 13 is disposed in close relation to the side of casing 8, where it is affected by intense heat, thereby preventing the vapor 35 from cooling and insuring an even delivery of vapor to the chamber in burner 6. The bulges 10^a, as has been stated, afford space for conduit 13 and are so small that they do

not give the heated vapor within the coil a chance to cool in circulating the several convolutions. 40

The entire device is supported from the burner chamber 6 which forms the base of the device. My device, therefore, can be set up on any supporting surface without requiring a frame or mountings of any sort. 45

From the above description it will be seen that I have invented a simple but highly efficient oil burner capable of wide general usage which vaporizes and burns the fuel 50 with a very high degree of efficiency.

It will of course be understood that various changes may be made in the form, details, proportion and arrangement of parts without departing from the scope of my invention. 55

What is claimed is:

A liquid fuel burner comprising a hollow burner head having a discharge passage through one side thereof, a perforated 60 tubular combustion chamber mounted concentrically with said burner head and spaced therefrom, a vaporizing coil closely encircling said combustion chamber, the convolutions of said coil being provided with 65 vertically aligned outwardly extending bulges affording arcuate recesses between said chamber and said coil, a vertical conduit connecting the uppermost convolution of said coil with said burner head extending through 70 said recesses, and means for connecting the lowermost convolution of said coil with a source of fuel supply.

In testimony whereof he does affix his signature.

ERVIN E. SPLETER.
